ABRADING TOOL

Filed April 23, 1929

UNITED STATES PATENT OFFICE

JAMES E. SIMS, OF SANTA ANA, CALIFORNIA

ABRADING TOOL

Application filed April 23, 1929. Serial No. 357,485.

This invention relates to an abrading tool and is particularly adaptable for honing piston pin holes and cylinders of internal combustion engines.

5 An object of the invention is to provide, a tool which is adapted to be attached to a rotating source of power and projected into the opening to be smoothed or may be fixed in a vise and the work rotated thereabout.

10 Another object of the invention is to provide for a rigid abrading surface that permits convenient arrangement of a detachable abrading seat so that the same may be replaceable while at the same time modifying 15 the parts so as to prevent cutting of the abrading sheet.

Other objects of the invention, are to provide, in a manner as hereinafter set forth, a tool of the character referred to, which is 20 strong, compact and durable, very simple in its method of assembly, convenient to operate, formed of simplified parts, which is thoroughly reliable in its operation and comparatively inexpensive to manufacture and 25 operate.

With the foregoing and other objects in view, the invention consists of a novel construction, combination and arrangement of parts, as will be hereinafter more specifically 30 described and illustrated in the accompanying drawings, wherein is disclosed an embodiment of the invention, but it is to be understood that changes, variations and modifications may be resorted to without departing 35 from the spirit of the claims hereunto appended.

In the drawings wherein like reference characters denote corresponding parts throughout the several views;

40 Figure 1 is an elevation, partly in section of the device in accordance with this invention,

Figure 2 is a side elevation of the sleeve thereof, and

45 Figure 3 is a fragmentary diametric sectional view of a portion thereof.

Referring to the drawings in detail, 5 indicates an elongated mandrel cylindrical in cross section having reduced peripherally 50 threaded portions 6, 7 at its opposite ends,

while the one threaded portion 7 merges into a shank 8 having a square shoulder 9 on the free extremity thereof. The shoulder 9 is recited as being square, it may be of any contour depending upon the configuration of 55 the gripping member to which the tool is adapted to be applied.

A pair of sockets 10, 11 are countersunk in the periphery of the mandrel 5, extends axially thereof and are disposed at an angle 60 with respect to the diameter of said mandrel. A pair of U-shaped resilient metallic clips 12, 13 are adapted to be anchored in the sockets 10, 11 and held therein by the friction of the resilient legs of the clip pressing 65 outwardly against the walls of the socket.

The friction of the legs however are not enough to prevent the movement of the clip, when it is desired to remove them for the 70 purposes to be presently referred to.

A substantially rigid, split, tubular sleeve 75 circumscribed about and supported on the mandrel 5. The length of the sleeve 14 however is slightly greater than the length of mandrel 5 to form an abutment engageable with the fastening devices and to be presently referred to. The slot 15 on the sleeve is 80 axially disposed and is of the same width, and is disposed at the same angle as the pair of sockets 10, 11.

Referring to Figure 3 of the drawings, this mandrel rotates in a clockwise direction and the leading corners of the slot 15 are rounded as at 16 to prevent cutting the abrading sheets, to be presently mentioned, by abutment with external objects. The walls of the sleeve 14 taper gently from the inner end 17 to the outer end 18 so that particular spots may be smoothed without exerting pressure on the 85 entire opening being honed.

A pair of nuts 19, 20 threadably engage and are supported on the threaded portions 6, 7 at the opposite ends of the mandrel and the inner faces of the nuts are brought into detachable abutment with the opposite ends 17, 95 18 of the sleeve 14 whereby the sleeve is securely held on the mandrel.

A sheet of abrading cloth 21 of the length of the sleeve 14 is trained over the outer surface thereof. The free ends of the sheet are 100

threaded through the slot 15 of the sleeve 14 and secured between the resilient legs of the U-shaped clips 12, 13, whereupon the abrading cloth 21 is demountably circumposed about the sleeve 14. The clips 12, 13 may be removed from the sockets 10, 11 when the ends of the abrading sheet 21 are inserted therein and after which the clips 10, 11 may then be inserted in the sockets of the mandrel 5.

10 It is pointed out that it is within the contemplation of the invention to utilize any suitable abrading sheet 21, the flexibility of which permits its adaptation to the purposes of this invention.

15 The tool is inserted in the opening which needs honing or dressing and the end 9 may be inserted in an electric drill and drill press or any other source of power whereupon the rotation of the sleeve 14 with the abrading sheet 21 thereon will smooth the surface considerably. Should it be desired to rotate the work about the sleeve 14, the shoulder 9 may be secured in a vise jaw in 20 fixed relation whereupon the rotation of the work about the sleeve will smooth the surface to be honed or dressed to the desired degree of smoothness.

Having described my invention, what I 30 claim as new is:

1. An abrading tool of the character referred to comprising a solid cylindrical mandrel having reduced threaded portions at its opposite ends, the threaded portion at one end merging with a shank, the shank having means at its outer end of angular contour and adapted to be gripped by an extraneous object to rigidly secure said mandrel thereto, said mandrel formed with a pair of circumferentially spaced sockets extending axially thereof, a pair of resilient clips frictionally supported in said sockets, an axially slotted tubular sleeve mounted on the mandrel, said slot registering with said pair of sockets, a sheet of abrading material circumposed on said sleeve and having the side edges thereof trained through said slot and anchored in said clips, a pair of nuts mounted on the threaded portions of said mandrel in abutment with the ends of said sleeve for securing said sleeve to said mandrel.

2. An abrading tool of the character referred to comprising a solid cylindrical mandrel having reduced threaded portions at its opposite ends, the threaded portion at one end merging with a shank, the shank having means at its outer end of angular contour and adapted to be gripped by an extraneous object to rigidly secure said mandrel thereto, said mandrel formed with a pair of circumferentially spaced sockets extending axially thereof, a pair of resilient clips frictionally supported in said sockets, an axially slotted tubular sleeve mounted on the mandrel, said slot registering with said pair of

sockets, a sheet of abrading material circumposed on said sleeve and having the side edges thereof trained through said slot and anchored in said clips, a pair of nuts mounted on the threaded portions of said mandrel in abutment with the ends of said sleeve for securing said sleeve to said mandrel, said sockets and slot disposed at an angle with respect to the diameter of the mandrel.

3. An abrading tool of the character referred to comprising a solid cylindrical mandrel having reduced threaded portions at its opposite ends, the threaded portion at one end merging with a shank, the shank having means at its outer end of angular contour and adapted to be gripped by an extraneous object to rigidly secure said mandrel thereto, said mandrel formed with a pair of circumferentially spaced sockets extending axially thereof, a pair of resilient clips frictionally supported in said sockets, an axially slotted tubular sleeve mounted on the mandrel, said slot registering with said pair of sockets, a sheet of abrading material circumposed on said sleeve and having the side edges thereof trained through said slot and anchored in said clips, a pair of nuts mounted on the threaded portions of said mandrel in abutment with the ends of said sleeve for securing said sleeve to said mandrel, said sockets and slot disposed at an angle with respect to the diameter of the mandrel.

4. An abrading tool of the character referred to, comprising a solid cylindrical mandrel having reduced threaded portions at its opposite ends, the threaded portion at one end merging with a shank, the shank having means at its outer end of angular contour and adapted to be gripped by an extraneous object to rigidly secure said mandrel thereto, said mandrel formed with a pair of circumferentially spaced sockets extending axially thereof, a pair of resilient clips frictionally supported in said sockets, an axially slotted tubular sleeve mounted on the mandrel, said slot registering with said pair of sockets, a sheet of abrading material circumposed on said sleeve and having the side edges thereof trained through said slot and anchored in said clips, a pair of nuts mounted on the threaded portions of said mandrel in abutment with the ends of said sleeve for securing said sleeve to said mandrel, said sockets and slot disposed at an angle with respect to the diameter of the mandrel, said resilient clips being U-shaped having the ends of the sheet frictionally held between the legs, the leading corners on said slot being rounded to prevent cutting of the abrading sheet.

In testimony whereof I affix my signature.

JAMES E. SIMS.
